UNITED STATES PATENT OFFICE.

ISAAC S. BETTS, OF NEW YORK, N. Y., ASSIGNOR TO HOUSEHOLD GUIDE CORPORATION,
OF NEW YORK, N. Y.

DESIGN FOR A COVER FOR PUBLICATIONS.

Application filed October 10, 1927. Serial No. 23,704. Term of patent 3½ years

To all whom it may concern:

Be it known that I, ISAAC S. BETTS, a citizen of the United States, residing at New York, county of New York, and State of New York, have invented a new, original, and ornamental Design for a Cover for Publications, of which the following is a specification, reference being had to the accompanying drawings, forming a part thereof.

In the drawings:

The figure is a plan view of a cover for publications showing my new design.

I claim:

The ornamental design for a cover for publications as shown.

ISAAC S. BETTS.
